RANGE FINDER

Otto K. Cazin, Hoboken, N. J., assignor to Universal Camera Corporation, New York, N. Y., a corporation of Delaware

Application December 29, 1939, Serial No. 311,510

6 Claims. (Cl. 88—3.4)

This invention relates generally to range finders. More particularly, this invention relates to range finders of the superimposed image type.

One of the objects of this invention is to provide a range finder of the character described, in which there is provided a movable mirror and improved means for mounting the mirror so that it may be moved in two planes of adjustment.

Another object of this invention is to provide a range finder of the type herein described, which shall be characterized by its novelty and simplicity of construction and which shall at the same time be highly efficient.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which is shown one of the various possible embodiments of this invention,

Fig. 1 is a top plan view of a range finder constructed in accordance with this invention and illustrating the manner of its use;

Fig. 2 is an enlarged view of the device shown in Fig. 1, but with one casing wall removed disclosing the interior construction;

Fig. 3 is a top plan elevational view of the device shown in Fig. 2;

Fig. 4 is an enlarged detail of a portion of the device shown in Fig. 2;

Fig. 5 is a cross-sectional view taken substantially on the line 5—5 of Fig. 4, but including the casing wall shown as removed in Figs. 2 and 4; and

Fig. 6 is a sectional view of a portion of the apparatus shown in Fig. 5 but illustrating a modified form of my invention.

In the drawing there is disclosed a range finder 10 constructed in accordance with this invention and which in this case is of the type adapted for use in connection with photographic or similar work. In this type of range finder two images of the object under observation are brought into superimposed relationship by mechanical means to automatically indicate or determine the range or distance.

The range finder 10 shown in the drawing comprises an elongated substantially rectangular hollow casing or frame, which may be die-cast in one piece, comprising the side walls 11, 12, end walls 13, 14 and a bottom wall 15, leaving

the top of the casing open. A removable wall 16 (see Fig. 5) is provided which serves as a closure for the top of the casing, the said wall 16 being designed to rest upon an internal peripheral shoulder 17, disposed adjacent the top edges of the side and end walls 11, 12 and 13, 14 respectively, to shut out light and dust particles. The closure 16 may be detachably fastened in position by means of the screws 18, received in correspondingly threaded openings 19 and 20. The opening 19 is disposed in a plate portion 21 integral and flush with the shoulder 17, while the opening 20 is disposed in a plate 22 fixedly attached to a recessed shoulder portion 15 of the end wall of the casing 14.

The opposite walls 11 and 12 of the casing are provided with optically aligned apertures 24 and 25, which are adapted to serve as viewing apertures for the range finder. To facilitate such viewing, an eye piece 26 is provided on the wall 12, the said eye piece being preferably integrally cast with the said wall 12. To prevent dust particles from entering the interior of the casing through the apertures 24 and 25, suitable transparent closure members 30 housed in frames 27 and 28 are provided. Disposed in the path of the line of vision between the apertures 24 and 25 is a mirror member 31 fixedly attached by adhesive or other suitable means at the upper edge thereof to the plate 21, and at opposite side edges to the walls 11 and 12. The mirror member 31 is of the type having a mirrored reflecting surface 31a on one side thereof and which is at the same time transparent, so that an object may be viewed directly therethrough. It is noted that the mirror member 31 is disposed in a plane at an angle of approximately 45° to the line of vision.

Mounted in the casing at the opposite end from that of the mirror 31 is a second mirror member 32, differing from the mirror member 31 by the fact that it has merely a reflecting surface 32a on one side thereof and is not transparent. The mirror 32 is angularly disposed in a direction which may be substantially parallel to that of the mirror 31. An aperture 33 is provided in the wall 11, similar to the aperture 24, protected by a transparent closure member 35 housed in a frame 34. It is thus seen that, when viewing an object through the eye piece 26, two images of the same object are seen, one image being seen directly through the transparent mirror 31 and the other image being received on the mirror surface 31a by reflection from the mirror surface 32a.

In the type of range finder herein described, it is necessary to superimpose the image of the object seen directly through the apertures 24 and 25 and the image reflected from the mirror 32. This is accomplished by rotating the mirror member 32 about a fixed vertical axis, as viewed from Fig. 5. The following mechanism is provided for effecting such rotational movement.

Journalled between the bottom wall 15 and a mounting plate 36 is a pivot shaft 37. Fixed to the shaft 37 for rotation therewith is a cam member 38, having a portion 38a thereof projecting through an aperture 39 in the casing wall 11. The plate 36 may be retained in position by means of a pair of screws 40a received in correspondingly threaded apertures in a pair of lugs 40, which may be integral with the walls 11, 12. One end of the cam 38 is provided with a finger portion 38b, which is adapted to contactively engage a finger portion 41a of a lever 41, the said lever 41 being mounted on a rotatable pivot member 42 journalled between the bottom casing wall 15 and a plate 22 fixedly attached at one end thereof to the inner shoulder of the end casting wall 14, by means of the screws 23.

It is thus seen from the above description that when the cam 38 is rotated in a counter-clockwise direction, as viewed from Fig. 2, the finger portion 38b thereof will engage the finger 41a of the lever 41, to cause pivotal movement of the said lever 41 in a clockwise direction. Mounted on the lever 41 for movement therewith is a mirror supporting member 43, which is substantially Z-shaped in cross-sectional contour, the lower portion 43a thereof being fixedly attached to the lever 41 by means of a set screw 44. The upper portion 43b of the member 43 is provided with a set screw 45, the bottom end of which is adapted to contactively engage the pivot 42, as shown in Fig. 2 of the drawing. The mirror 32 is rigidly attached to the member 43 by any suitable attaching means, such as for example adhesive means.

It is thus seen that when the lever 41 is pivotally moved, the mirror 32 will be correspondingly rotated about the pivot 42, due to the fact that its supporting member 43 is rigidly fixed to the lever 41 by means of the set screws 44 and 44a.

To cause rotational movement of the cam 38, there is provided a disc 47, rotatably mounted in the wall 11. The disc 47 is provided on the inner surface thereof with a raised cam portion 48, which is designed to cooperate with the portion 38a of the cam 38, in such a manner that when the disc 47 is rotated in one direction, such as for example toward the left, as viewed from Fig. 2, the cam 38 will pivot about the axis 37 in a counter-clockwise direction, to cause movement of the lever 41 in a clockwise direction.

For maintaining the fingers 38b and 41a in constant engagement, there is provided a spring 50, one end of which is connected to the cam 38 and the opposite end of which is connected to the lever 41. It is noted that the spring normally urges the movement of the lever 41 in a counter-clockwise direction, and the cam 38 also in a counter-clockwise direction, to cause the portion 38a thereof to remain in cooperative engagement with the cam 48 at all times. Due to the action of the spring 50, it is also noted that when the disc 47 is rotated in the opposite direction (to the right), the lever 41 will be moved in a counter-clockwise direction.

The amount of rotational movement of the disc 47 necessary to move the mirror about the pivot

42 to superimpose the two images will indicate the range or distance at which the object is from the range finder. The surface of the disc 47 may be provided with properly arranged indicia, representing distances in feet or in other denominations, so that when the disc 47 comes to rest in such position where the two images are superimposed, the particular mark on the disc 47 in alignment with a permanent marker member 51, mounted on the wall 11, will indicate the range or distance.

The bottom casing wall 15 may be provided with integral raised portions 70 and 71, to space the lever 41 from the bottom wall 15 and thus avoid friction.

In accordance with the present invention, there is provided novel means for adjustably positioning the movable mirror 32 in two planes of adjustment, one the movement about the pivot 42 and the other in tilting direction with respect thereto. To adjustably move the mirror 32 about a vertical axis, or in other words about an axis parallel with the axis of the pivot 42, it is merely necessary to loosen the set screw 44 and to move the member 43 carrying the mirror 32 about the set screw 44a, as a pivot, until both images are superimposed or lie in the same vertical plane, after which the set screw 44 may be tightened again. To permit such relative movement between the member 43 and the lever 41, there is provided an over-sized aperture 52 in the portion 43a of the member 43, through which the shank of the set screw 44 passes.

To adjustably move the mirror 32 in a plane at right angles to the path of movement just mentioned, or about a horizontal axis, it is merely necessary to turn the set screw 45 in one direction or the other, until both images are superimposed or lie in the same horizontal plane. Due to the fact that the set screw 45 is in constant contact with the pivot 42, it is seen that if the set screw 45 is turned in a clockwise direction, as viewed from Fig. 5, the portion 43b of the member 43 will move in a direction away from the plate 22, to cause inward tilting of the mirror 32. If the set screw 45 is moved in a counter-clockwise direction, the mirror 32 will be caused to tilt in the opposite direction.

In Fig. 6 I have shown a modified construction for adjustably moving the mirror 32 about a horizontal axis. In this form of my invention, instead of the set screw 45 being threadedly carried by the mirror supporting member 43, I provide a set screw 73 passing freely through a slotted opening 71 in the supporting member 43 and threadedly received in a threaded opening 72 in the pivot shaft 42'. The mirror 32, after adjustment, will thus rotate with the pivot 42' and set screw 73.

Since the range finder is adapted for use in connection with a camera, there has been provided a mounting member 60 comprising a portion 60a designed to cooperate with a clip member fixed to the camera casing and a collar portion 60b relatively movably encircling a portion of the eye piece 26. To retain the member 60 on the eye piece 26, there is provided a retaining member 61 having a portion 61a disposed adjacent the outer edge of the collar 60b and encircling the eye piece 26, the said member 61 being attached to the wall 12 by means of the screw 62. The member 60 is so designed that the range finder may be tiltedly moved so as to be used in either a horizontal position, as shown in Figs. 2 and 3, or in a vertical posi-

tion. To retain the mounting 60 in either a horizontal or vertical position, there may be provided cooperating pairs of projections and detents 63 and 64 on the clip 61 and on the collar 60b.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a range finder or like instrument wherein in the measurement of range is effected by superimposing a pair of images of the same object and in which a rotatably mounted mirror is employed, means to adjustably move said mirror about a vertical axis to position both images in superimposed relationship in a vertical plane, means to adjustably move said mirror about a horizontal axis to position both images in superimposed relationship in a horizontal plane, said last named means comprising a mirror supporting member, a threaded member mounted on said supporting member, and abutment means coincident with said vertical axis and cooperating with said threaded member whereby rotational movement thereof will tiltably move said mirror.

2. In a range finder or like instrument wherein in the measurement of range is effected by superimposing a pair of images of the same object and in which a rotatably mounted mirror is employed, means to adjustably move said mirror about a vertical axis to position both images in superimposed relationship in a vertical plane, means to adjustably move said mirror about a horizontal axis to position both images in superimposed relationship in a horizontal plane, said last named means comprising a rotatably mounted shaft, a mirror supporting member, and a threaded member engaging with said shaft whereby the said mirror supporting member is fixedly attached to the said shaft for rotation therewith after such adjustment.

3. In a range finder or like instrument wherein in the measurement of range is effected by superimposing a pair of images of the same object and in which a rotatably mounted mirror is employed, means including a shaft to adjustably move said mirror about a vertical axis to position both images in superimposed relationship in a vertical plane, means to adjustably move

said mirror about a horizontal axis to position both images in superimposed relationship in a horizontal plane, said last named means comprising a mirror supporting member, a threaded member mounted on said supporting member, and abutment means on said shaft for said threaded member whereby rotational movement of said threaded member will tiltably move said mirror.

4. In a range finder or like instrument wherein in the measurement of range is effected by superimposing a pair of images of the same object and in which a mirror is mounted for rotation about a pivot shaft, means to adjustably maintain said mirror in a selected position for movement about a vertical axis, said selected position being such that both images will be in superimposed relationship in a vertical plane, means to adjustably maintain said mirror in a selected position with respect to a horizontal axis and for movement about said vertical axis, said last named selected position being such that both images will be in superimposed relationship in a horizontal plane, said last named means comprising a member threadedly received in said pivot shaft.

5. In a range finder or like instrument wherein in the measurement of range is effected by superimposing a pair of images of the same object and in which a mirror is mounted for rotation about a pivot shaft, means to adjustably maintain said mirror in a selected position for movement about a vertical axis, said selected position being such that both images will be in superimposed relationship in a vertical plane, means to adjustably maintain said mirror in a selected position with respect to a horizontal axis and for movement about said vertical axis, said last named selected position being such that both images will be in superimposed relationship in a horizontal plane, said last named means comprising a screw threaded member in axial alignment and in constant engagement with said pivot shaft.

6. In a range finder or like instrument wherein in a mirror is employed to reflect an image, a frame, means including a pivot for rotatably mounting said frame, a movable support, means for mounting said mirror on said support, said support comprising a substantially Z-shaped mirror supporting member mounted on said frame for rotation about a vertical axis parallel to said pivot and held in adjusted position by a set screw passing through an oversized aperture in said member and engaging said frame, and a set screw mounted in a leg of said member and cooperating with said pivot to adjust said mirror about a horizontal axis.

OTTO K. CAZIN.
